UNITED STATES PATENT OFFICE

2,499,968

PNEUMATIC-HYDRAULIC PRESSURE
CONVERTER

Edward M. Pfauser, Elm Grove, Wis., assignor to
Blackhawk Mfg. Co., Milwaukee, Wis., a corporation of Wisconsin

Application December 8, 1945, Serial No. 633,705

4 Claims. (Cl. 60—54.6)

1

This invention relates generally to improvements in systems for transmitting pressure from supply sources to zones of utilization, and relates more specifically to an improved pneumatically actuated hydraulic ram assemblage.

The primary object of my invention is to provide an improved fluid pressure actuated ram assemblage which is simple and compact in construction, and which is moreover highly efficient in operation and flexible in its adaptations.

In commercial garages and other institutions where abundant air under pressure is available, it is frequently desirable to also have available for immediate use, rams or similar pressure applying devices which are adapted to be operated from the air pressure supply source and which are also relatively compact but powerful and adapted to be actuated in any position and in cramped localities. Relatively small and universally movable hydraulic rams are best suited for such purposes, but it is desirable in order to permit unobstructed use of such rams, to provide portable power transmitting means for converting the air pressure from the source of supply into hydraulic pressure within the ram; and to also provide readily manipulable control means for effecting normal operation of the system. No system for effectively accomplishing these desirable results has heretofore been commercialized without introducing many complications.

It is therefore a more specific object of the present invention to provide an improved system of the above-mentioned type, which most effectively meets all requirements and which is in fact exceedingly reliable in operation.

Another specific object of this invention is to provide an improved unit for effectively converting air pressure into hydraulic pressure in concentrated form, and which is universally movable and highly attractive in appearance.

A further specific object of the invention is to provide improved ram actuating and control mechanism which is conveniently manipulable for the purpose of performing diverse classes of work.

Still another specific object of my invention is to provide a durable pneumatically actuated hydraulic ram unit, which is flexible in its adaptations and which may be manufactured and sold at moderate cost.

These and other specific objects and advantages of the invention will be apparent from the following detailed description.

A clear conception of the several features constituting my present invention, and of the con-

2

struction and operation of a typical system embodying the same, may be had by referring to the drawing accompanying and forming a part of this specification wherein like reference characters designate the same or similar parts in the various views.

Fig. 1 is a somewhat diagrammatic side elevation of a typical pneumatically actuated hydraulic ram assemblage embodying the invention;

10

Fig. 2 is an enlarged longitudinal central vertical section through the improved pressure converter for transforming the air pressure into hydraulic pressure; and

15

Fig. 3 is an enlarged central vertical section through the control valve of the system, showing the valves in reverse position as compared to the disclosure in Fig. 1.

While the invention has been shown and de-

20

scribed herein as being especially applicable to a portable unit for pneumatically actuating simple hydraulic rams with the aid of air under pressure, it is not my desire or intent to thereby unnecessarily restrict the utility of the invention

25

since some of the improved features may be more generally applicable.

Referring to Fig. 1 of the drawing, the improved typical pneumatically actuated hydraulic ram system shown therein, comprises in general

30

any suitable source or supply of air under pressure such as a pipe line 5 communicating with a compressor or storage reservoir; a pressure converter and transmitter 6 for transforming air pressure derived from the pipe line 5 into hydraulic pressure; a control valve assemblage 7 interposed at any convenient location between the pipe line 5 and the converter 6; and a hydraulic ram 8 operable by hydraulic pressure derived from the converter 6.

40

The improved pressure converter 6 is preferably of light but durable and portable construction as shown in detail in Fig. 2, and consists primarily of a triple section streamlined casing comprising front and rear and intermediate co-

45

axial sections 9, 10, 11 respectively; an air pressure actuated piston 12 slidable within a relatively large air cylinder 13 firmly but detachably connecting the end casing sections 9, 10; a hydraulic pressure transmitting piston 14 slidable within a

50

relatively small hydraulic cylinder 15 detachably mounted within the forward portion of the front casing section 9 by means of a fitting 16, and being releasably connected to the air piston 12 by a piston rod 17; and a helical compression spring 18 loosely surrounding the cylinder 15 and co-

55

acting at its opposite ends with the air piston 12 and casing section 9 respectively.

The cylinders 13, 15 are of approximately the same length and may be formed of light but durable tubing of proper internal diameter, and the rear casing section 10 is provided with a central air inlet port 19 with which the control valve assemblage 7 may be either directly associated, or connected thereto by means of a flexible air conducting tube 20 as shown. The air piston 12 is snugly slidably cooperable with the cylinder 13 and is provided with any suitable type of conventional packing 21; and the rear end of this piston 12 is cooperable with a central abutment 22 formed on the casing section 10 near the port 19 so as to limit the rearward piston travel as shown in dot-and-dash lines, while the front peripheral portion of the air piston 12 is cooperable with the front casing section 9 in order to limit the forward piston stroke as shown in solid lines in Fig. 2. The rear casing section 9 and the port 19 are in constant open communication with the rear displacement chamber of the air cylinder 13; and the front casing section 9 within which the spring 18 is confined, should be provided with an air vent 23.

The opposite ends of the tubular air cylinder 13 have screw thread coaction with the adjacent ends of the front and rear casing sections 9, 10, and these threaded cylinder ends serve to firmly clamp the intermediate casing section 11 between the two end sections 9, 10; and the front end of the hydraulic cylinder 15 has screw thread coaction with the fitting 16 which is attached by other screw threads to the forward end of the front casing section 9. The entire converter unit is thus adapted to be readily assembled or dismantled, and the fitting 16 is provided with a liquid conducting port 24 adapted to be connected to the ram 8 by means of a staunch but flexible high pressure hose 25 of any suitable length. The hydraulic piston 14 is provided at one end with a cup-packing 26 which is exposed to the port 24, and this piston is snugly slidably cooperable with the bore of the cylinder 15, and is also provided at its opposite end with a spherical socket with which the ball-shaped front end 27 of the piston rod 17 is releasably cooperable. The rod 17 is loosely slidable within the hydraulic cylinder 15, and has its rear end 28 threaded for rigid attachment to the air piston 12 with the aid of a lock nut 29. With this assemblage of elements, the hydraulic piston 14 may move within the cylinder 15 independently of the air piston 12, and will not be drawn rearwardly by the air piston when the latter moves rearwardly, since the rod end 27 is adapted to be withdrawn from the socket within the hydraulic piston 14. This releasable connection between the spherical end 27 of the rod 17 and the hydraulic piston 14 permits the air piston 12 to be forced by the spring 18 to the extreme right as viewed in Fig. 2, upon release of the air pressure acting upon the piston 12, without correspondingly moving or withdrawing the piston 14 and thereby creating a vacuum in the hydraulic system such as might cause air to be admitted and trapped within this system; and the releasable connection also permits the piston 14 to be readily removed from the cylinder 15 for re-packing without disturbing the rod 17 and piston 12.

In order to facilitate transportation and manipulation of the pressure transmitter 6, the medial casing section 11 is provided with a carrying handle 30, and the sections 11, 9 may also be

provided with a shoulder strap 31 as shown. In addition to the handle 30 and strap 31, the converter unit casing may be provided with a pair of front supporting wheels 32 associated with the front section 9, and with a central rear skid block 33 secured to the intermediate section 11, or with additional wheels 32 in substitution for the block 33. These supports will permit the operator to pull the converter 6 along the ground with little effort when the ram 8 is being utilized in cramped quarters remote from the fixed air supply line 5.

As previously indicated, the improved control valve assembly 7 may either be mounted directly upon the rear casing section 10 adjacent to the port 19, or the control valve may be mounted on a flexible branch air supply hose 34 and connected to the port 19 by a flexible hose or tube 20, and the details of the control valve assemblage are disclosed in Fig. 3. This control valve assemblage 7 is very simple and compact and comprises merely a body 35 having opposed passages 36, 37 in its opposite ends and an air escape port 38 near the passage 37; and two similar manually opened spring closed poppet valves 39, 40 interposed between the passages 36, 37 and between the passage 37 and the port 38 respectively. The valve 39 is an air pressure inlet control valve, and is provided with an actuating stem and button 41, being normally urged toward closed position by a compression spring 42 and air under pressure coacting with the valve and with a screw plug 43. The valve 40 is an air pressure exhaust valve, being provided with another actuating stem and button 44 and likewise being normally pressed to its seat by a compression spring 45 and back pressure coacting therewith and with another screw plug 46. The two valve chambers are interconnected by a conduit 47 and the stem of the valve 39 is preferably provided with a packing 48; and the valve arrangement is such that when the valve 39 is opened, air under pressure will be admitted to the converter 6 from the passage 36 through the conduit 47 and passage 37 while the valve 40 remains closed, whereas opening of the valve 40, while the valve 39 remains closed, will cause compressed air from the converter 6 to escape to the atmosphere through the passage 37 and port 38.

The hydraulic ram 8 which is operable by liquid under pressure delivered from the converter 6 by the piston 14 through the fitting port 24 and hose 25, is of relatively simple construction and comprises primarily a universally movable cylinder 49, and a ram plunger 50 slidably confined within the cylinder 49. The hose 25 communicates with the closed end of the plunger displacement chamber remote from the movable plunger, and if so desired, the ram plunger 50 may be provided with a return spring in a well known manner. The ram assemblage should be of light but durable construction, adapted to operate in any selected position and it is to be noted that whenever pressure is applied to the hydraulic piston 14, the liquid within the hose 25 and cylinder 49 will be compressed and will tend to move the plunger 50 outwardly, whereas application of pressure to the ram plunger 50 when the piston 14 is released, will cause this piston 14 to be moved rearwardly within the cylinder 49. When the improved pneumatically actuated hydraulic ram system has been properly constructed and assembled as in Fig. 1, the control valves 39, 40 will normally be closed, and the converter 6 and ram 8 may be moved about freely and disposed in any desired position. The

ram plunger 50 and cylinder 49 may then be transposed between an object to which pressure is to be applied and any suitable reaction surface, whereupon pneumatic pressure may be admitted to the air piston 12 by merely opening the valve 39 with the aid of the push-button 41. As the air pressure acts upon the piston 12 it compresses the spring 18 and forces the hydraulic piston 14 forwardly through the piston rod 17, thereby subjecting the hydraulic system to high pressure and causing the ram 8 to do its work. When it becomes desirable to release the pressure within the ram 8, it is only necessary to release the button 41 and to press the button 44, whereupon the spring 42 will close the valve 39 and prevent further ingress of compressed air, while the open valve 40 will permit air to escape from the converter through the tube 20, passage 37 and port 38, to the atmosphere. Release of both buttons 41, 44 will again place the apparatus in normal condition, and it is to be observed that when the air pressure from within the converter 6 is released, the spring 18 quickly becomes effective to move the piston 12 into its rearmost position, without affecting the position of the hydraulic piston 14. However, when the piston 12 has been thus withdrawn, application of pressure to the ram plunger 50 will cause the hydraulic piston 14 to move rearwardly within the cylinder 15.

From the foregoing detailed description, it will be apparent that my present invention provides a new and useful pneumatic hydraulic ram system which is exceedingly simple and compact in construction and which is moreover highly efficient in operation and flexible in its adaptations. The converter unit 6 and the ram 8 may obviously be readily transported and disposed in any desired position, and the pressure transmitter functions to effectively convert relatively low pneumatic pressure into high hydraulic pressure at the ram 8. The converter 6 besides being of highly aesthetic appearance and readily transportable and manipulable, may be quickly assembled and dismantled so as to gain access to all portions of the apparatus, and the control valves 39, 40 being of simple and interchangeable construction, reduce the cost of manufacture of the assemblage to a minimum. The releasable connection between the air piston 12 and the hydraulic piston 14 eliminates the possibility of having air enter the hydraulic system, and the vent 23 serves to positively prevent confinement of air in front of the air piston 12. The fitting 16 besides providing a rigid support for the hydraulic cylinder 15, permits convenient removal of this cylinder and of the hydraulic piston 14 therein, and all parts of the apparatus are of durable construction and may be manufactured at moderate cost. The use of the thin tubular section 11 and cylinders 13, 15, provides a light but strong portable structure in which the section 11 effectively protects the thin cylinder against possible indentation or damage due to rough usage. The improved ram system has proven highly satisfactory in actual use and can be utilized to perform diverse types of work.

It should be understood that it is not desired to limit this invention to the exact details of construction or to the precise mode of operation herein shown and described, for various modifications within the scope of the claims may occur to persons skilled in the art.

I claim:

1. A pneumatic-hydraulic pressure converter comprising, an elongated casing having coaxial

opposite end sections and a thin tubular intermediate section loosely abutting the adjacent ends of the end sections, a thin tubular air cylinder disposed within said intermediate section and having its opposite ends screw-threaded within said end sections to unite the latter and to clamp the intermediate section in place, a hollow fitting detachably secured to the extreme end of one of said end sections remote from said air cylinder, a thin tubular hydraulic cylinder of lesser diameter than the interior of said air cylinder and the exterior of said fitting secured to and supported at one end from the fitting while its opposite free end extends centrally within the air cylinder, and cooperating air and hydraulic pistons slidable in said air and hydraulic cylinders respectively.

2. A pneumatic-hydraulic pressure converter comprising, an elongated casing having coaxial opposite end sections and a thin tubular intermediate section surrounding and loosely abutting the adjacent ends of the end sections, a thin tubular air cylinder disposed within and spaced from said intermediate section and having its opposite ends screw-threaded within said end sections to unite the latter and to clamp the intermediate section in place, a hollow fitting detachably secured within the extreme end of one of said end sections remote from said air cylinder, a thin tubular hydraulic cylinder of lesser diameter than the interior of said air cylinder and the exterior of said fitting secured to and supported at one end from the fitting while its opposite free end extends centrally within the air cylinder, and cooperating air and hydraulic pistons slidable in said air and hydraulic cylinders respectively.

3. A pneumatic-hydraulic pressure converter comprising, an elongated casing having coaxial opposite end sections and a thin tubular intermediate section surrounding and loosely abutting the adjacent ends of the end sections, a thin tubular air cylinder disposed within and spaced from said intermediate section and having its opposite ends screw-threaded within said end sections to unite the latter and to clamp the intermediate section in place, a hollow fitting detachably secured within the extreme end of one of said end sections remote from said air cylinder, a thin tubular hydraulic cylinder of lesser diameter than the interior of said air cylinder and the exterior of said fitting secured to and supported at one end from the fitting while its opposite free end extends centrally within the air cylinder, an air piston slidably cooperable with said air cylinder, a hydraulic piston slidably cooperable with said hydraulic cylinder, and a piston rod snugly slidably engaging said hydraulic cylinder and having one end rigidly attached to said air piston while its opposite end loosely contacts said hydraulic piston.

4. A pneumatic-hydraulic pressure converter comprising, an elongated outer casing having coaxial opposite cup-shaped end sections and a thin tubular intermediate section surrounding and loosely abutting the brims of the end sections, a thin tubular air cylinder disposed within and spaced from the interior of said intermediate section and having its opposite end screw-threaded within said cup-section brims to unite the latter and to clamp the intermediate section against the end sections, a hollow fitting detachably screw threaded within the base of one of said cup-sections remote from its brim, a thin tubular hydraulic cylinder of lesser diameter

than the interior of said air cylinder and the exterior of said fitting secured to and supported at one end from the fitting while its opposite free end extends centrally into the air cylinder, a cup-shaped air piston having its brim slidably cooperable with said air cylinder while its base is movable into the other of said cup-sections, a piston rod having one end rigidly secured within the base of said cup-shaped piston and being snugly slidably cooperable with said hydraulic cylinder, and a hydraulic piston slidable within the said hydraulic cylinder and loosely abutting the opposite end of said piston rod.
